UNITED STATES PATENT OFFICE

169,531

COOLING BASIN FOR AIR-CONDITIONING
UNIT

Marcus M. Cunningham, Houston, Tex., assignor
of one-third to John R. Main and one-third to
Alvin S. Moody, both of Houston, Tex.

Application January 10, 1952, Serial No. 17,999

Term of patent 14 years

(Cl. D62—4)

To all whom it may concern:

Be it known that I, Marcus M. Cunningham, a citizen of the United States of America, residing at Houston, Harris County, State of Texas, have invented a new, original, and ornamental Design for a Cooling Basin for Air-Conditioning Unit, of which the following is a specification, reference being made to the accompanying drawings, forming a part thereof.

Fig. 1 is a top plan view of a cooling basin for air-conditioning unit embodying my new design;

Fig. 2 is a side view thereof;

Fig. 3 is a reduced perspective view thereof.

I claim:

The ornamental design for a cooling basin for air-conditioning unit, as shown.

MARCUS M. CUNNINGHAM.
